UNITED STATES PATENT OFFICE.

CYRUS CHAMBERS, JR., AND WILLIAM MENDHAM, OF PHILADELPHIA,
PENNSYLVANIA; SAID MENDHAM ASSIGNOR TO SAID CHAMBERS.

PAPER-FOLDING MACHINE.

SPECIFICATION forming part of Letters Patent No. 225,506, dated March 16, 1880.

Application filed March 13, 1876.

To all whom it may concern:

Be it known that we, CYRUS CHAMBERS, Jr., and WILLIAM MENDHAM, both of Philadelphia, in the State of Pennsylvania, have invented certain new and useful Improvements in Rotary Paper-Folding Machines; and we do hereby declare the following to be a full and correct description of the same, reference being had to the accompanying drawings, in

10 which—

Figure 1 is a side elevation of the machine. Fig. 2 is a longitudinal vertical section on line xx of Fig. 3. Fig. 3 is a transverse vertical section on line yy of Fig. 2. Figs. 4, 5, 6, and

15 7 are details on an enlarged scale.

The same part is marked by the same letter of reference wherever it occurs.

The object of our invention is to provide a machine for the very rapid folding of damp 20 limp paper, either fed by hand or received mechanically from the printing-press.

It consists of improvements and modifications of the machine invented by us and patented August 5, 1873, numbered 141,489. In 25 that machine the first fold only was made by means of an elastic creasing-blade and spring-gripers attached to the first pair of folding-rollers and acting upon the sheet without arresting its motion. All the subsequent folds 30 were made in the ordinary manner by means of a folding-blade acting upon a sheet at rest above a pair of common folding-rollers.

In the machine now about to be described all the folds are imparted to the sheet by 35 rotating folding-blades and by gripers attached to the folding-rollers, all the movements of the machine being rotatory and continuous, thus insuring the highest practicable rate of speed in the performance of its work.

40 To enable others to make and use our improved folding-machine, we proceed to describe in detail its construction and operation.

In the accompanying drawings, Z marks a 45 strong frame-work, to which the operative parts of the machine are attached. An inclined table, T , receives the bank of paper to be folded when the machine is to be fed by hand. If fed direct from the printing-press, mechanism must be employed which, not being included in the present application, need

not now be described. The front edge of the sheet is placed against the stops s attached to the shaft of the drop-roller d . The drop-roller then descends and holds the edge against the surface of roller A , and the stops fall into 55 grooves e in the roller and disappear beneath its surface, and allow the further rotation of roller A to carry the sheet forward.

Thus far the construction and operation are the same as those of our machine of August 60 5, 1873, before referred to.

A B are the first pair of folding-rollers. The roller A turns on journals in the side framing, and its shaft is the main shaft of the machine, to which the driving-power, represented by the winch W , is applied. One end of the roller A consists of a toothed gear, which meshes into and drives gear A' , attached to the end of the shaft of the first rotating blade D . The gear A' rotates in the same time with 65 70 the roller A , and the blade D engages with roller A once at each rotation. Roller A is provided with a number of grooves, c , as shown, and in it is located a nipper-bar, d' , which vibrates on substantial journals in the 75 end of roller A . (See Fig. 4.) To one of these journals is attached a short lever, e' , in which is an adjustable stud, f' , on which rotates a friction-roller, g' , rolling in contact with a stationary cam, C , attached to the side framing, 80 and so timed that the griper-bar may be made to open and close at the desired periods during the rotation of the roller A .

A spring, S' , is applied to the heel of lever e' , to keep the roller g' in contact with the surface of cam C .

The nipper d' works against an angular edge of the recess in roller A , in which it vibrates, (see Figs. 4 and 5,) and the blade D enters between this angular edge and the nipper, so as 90 to force a crease of the sheet into the bite of the nipper when open.

When, by the further rotation of A and A' , the blade D is withdrawn, the nipper closes, and carries the sheet along with the roller A 95 till the crease enters the bite of rollers A B , when the nippers are opened and the sheet allowed to pass double between said rollers and along tapes under rods E to stop F . (See Fig. 2.) The forward end of the sheet, immediately af-

ter being fed over roller A and under the drop-
roller d, passes down between two sets of bars,
a b, inclined at an angle of about forty-five
degrees, the upper set, a, being made to re-
ciprocate longitudinally, so that when they
are in their highest position their upper ends
enter grooves c in the creasing-roller A and
prevent the entrance of the sheet between the
rollers A B, and when the bars a are in their
lowest position their upper ends are buried
in grooves in roller B, and give the sheet un-
obstructed access to the bite of the rollers A B.

This device replaces the vibrating guide-
fingers V, used for a similar purpose in our
15 machine of August 5, 1873.

The lower set of bars, b, are rigidly attached
to a cross-bar, Q', extending from side to side,
and attached to the lower framing. They ex-
tend up to the top of roller A, near the drop-
20 roller d, as shown in Figs. 1 and 2.

The upper set of bars, a, pass loosely through
holes in cross-bar Q', so as to move up and
down. They are fixed to a bar, G', (see Fig.
2,) attached to an arm, F', of rock-shaft E'.

25 A toothed pinion, R, on the end of the main
shaft engages with large gear S on the end of
cam-shaft B', carrying cam C', which operates
arm D' projecting from rock-shaft E'.

It is by virtue of this connection that the
30 bar G' at the end of arm F' receives its recip-
rocating movement at the proper time. A
spring, f, counteracts cam C, and tends to
force the bar Q' down when released from the
direct action of the cam.

35 When the sheet, once folded, has passed the
rollers A B it travels on tapes under rods E
till its folded edge encounters the stops F at
the rear of the machine. As the wet and
limp sheet is traveling at high velocity, it
40 would, if unrestrained, have a tendency to
double up when its folded edge struck the stop.
To avoid this difficulty we employ a device
for moderating its speed by a force applied
near the rear end of the sheet. We place at
45 a distance from the stop greater than half the
length of the longest sheet the machine is de-
signed to fold what we term "tail-catchers,"
which grasp the sheet near the rear end just
before the folded edge strikes the stop, so as
50 to arrest its rapid motion and allow it to reach
the stop at such a moderate velocity as to ob-
viate all tendency to double and wrinkle.
This device consists of a shaft, G, extending
across the front of the machine, and making
55 one revolution only for each sheet folded.
From this shaft project two or more adjusta-
ble arms or fingers, g, which are just of suffi-
cient length to come in contact with the lower
roll, H, and grasp or clamp the paper for an
60 instant between them, so as to reduce its speed
to the speed of the end of the said fingers.
The further rotation of the shaft G instantly
releases the paper preparatory to its receiving
the second fold.

65 In place of the roller H, there may, if pre-
ferred, be small independent friction-rollers
running in separate bearings and not driven,

and these may be located at less than half the
length of the sheet from the stop.

The device for giving the second fold con-
sists of a pair of rollers, I J, one, I, having
one or more grooves, h h, and carrying a creas-
ing-blade, and the other having a longitudi-
nal groove, K, for the reception of a rotating
creasing-blade, L, as clearly shown in Figs. 2 75
and 3. These two rolls, with their grooves h
h and blades j and L, make two parallel folds
at right angles to the first fold, the distance
between the grooves h h and the blade j, meas-
ured around the periphery of the roller I, de-
termining the distance between the two parallel
folds. The object of the second groove
is to allow a variation in that distance; or the
groove may, if preferred, be in a bar made ad-
justable around the periphery of the roll. 85

The rollers I J are geared together, and are
driven by a bevel-gear connection with the
tape-roller shaft, on the end of which is gear
H', which meshes into and is driven by gear S.
A gear, O', on the rear end of the shaft of
roller I engages with and drives a gear, L', on
the rear end of the shaft of blade L. From
the roll J the thrice-folded sheet passes be-
tween the rolls M M, and is carried by tapes
and bars to the near side of the machine over
the rolls N N', the sheet being stripped from
the groove K in the roller J by the stripper-
fingers O and guided around a roller, M, as
shown in Fig. 3. The rolls M M are geared
together, and are driven by a gear on the end
of the shaft of roller J. As the thrice-folded
sheet is presented above the rolls N N' it is
again folded at right angles by the rotating
creasing-blade P forcing the paper into the
stationary groove in the roller N. The rollers
N N' are geared together, and are driven by a
train of gearing, H' I' J' K', receiving motion
from gear S. The gears on rollers N N' drive
the shaft of rotating blade P. As the sheet
is drawn between the two rollers N and N' its
folded edge is stripped from the groove by the
stripper Q and delivered into the packing-box
in the usual manner. 95

The paste-pot R is located under the roller
A, opposite to the center of the sheet, with its
paste-wheel running in contact with it during
the passage of the last half of the sheet, the
paste-wheel coinciding in position with one of
the grooves c in roller A opposite the center
line of the sheet. The once-folded and pasted
sheet is trimmed at the head by a rotating
serrated cutter, which is to be the subject of
another application. 115

The grooves h h (see Fig. 7) are to be dis-
tinguished from the longitudinal grooves,
which are provided with nipper-bars. In the
nipper-bar grooves the crease of the paper is
held by the pressure of the nipper against the
edge of the groove or recess in which it works;
but in the grooves h h, which we have called
"stationary," the mouth being smaller than the
bottom of the cavity, the paper is held by
reason of the expansion of the fold itself after
it has passed the mouth of the groove and 130

entered the enlarged portion. This method of holding the crease becomes applicable when the elasticity of the fold has been increased by the doubling of the paper. We therefore 5 prefer to apply it after the first and second folds have been made.

The crease held in the longitudinal grooves of the folding-rollers is released by means of a device which we call a "stripper." It consists of a series of fingers attached to a back bar after the manner of a comb, and entering the circular grooves in the folding-rollers. As 10 the rollers turn the fingers are brought underneath the creased edge of the sheet, and gradually force it out of the groove in which it has 15 been held.

Fig. 6 illustrates a method of operating the griper-bar in a creasing-roller. On each end of the roller is attached a spring, z , provided 20 with a triangular tooth at its free end, which acts against the nipper-bar y to force it open when the spring is pressed down by the contact of the folding-rollers. A spring, x , reacts against the back of the nipper-bar to force 25 it into contact with the edge of the groove k , in which it acts.

The machinery and methods hereinbefore described having been in interference with claims to similar methods and machinery made 30 by other parties, we wish it to be understood that we make no claim to the mechanisms and methods described and claimed in the said interfering cases, otherwise than as herein specifically claimed.

35 Having thus fully described our invention, what we claim, and desire to secure by Letters Patent, is—

1. In combination with the grooved rollers A B, the inclined bars a b , for guiding the 40 loose end of the sheet from the roller A past

the roller B without permitting it to enter between them, as described.

2. The combination, with the cross-bar G' and arm F' , of the bars a , made to reciprocate longitudinally by the movement of the rock-bar E' , so as alternately to open and close the entrance to the bite of the rollers A B, as 45 specified.

3. In combination with mechanism or devices for carrying the sheet to the stop F, the 50 tail-catching mechanism, consisting of the fingers g g on shaft G , revolving at such speed as to come into contact with the surface of roller H once for each sheet which passes between them, as and for the purpose stated. 55

4. In combination with a blade for inserting the paper, a folding-roller having a longitudinal groove, made larger at the bottom than at the mouth for the purpose of allowing room for the fold of the paper to fly open and 60 be held in the groove by its own elasticity on the withdrawal of the blade which introduced it, as and for the purpose explained.

5. In combination with folding-rollers having longitudinal grooves formed with sharp 65 edges and an enlarged interior space, as described, the stripper-fingers entering the circular grooves in the rollers and forcing the fold of the sheet to leave the longitudinal groove, in the manner and for the purpose 70 pointed out and shown.

The above specification of our said invention signed and witnessed at Philadelphia this 10th day of March, A. D. 1876.

CYRUS CHAMBERS, JR.
WILLIAM MENDHAM.
